UNITED STATES PATENT OFFICE.

GEORGE MILNE, OF CHICAGO, ILLINOIS.

EXPLOSIVE-ENGINE.

1,088,292.

Specification of Letters Patent.

Patented Feb. 24, 1914.

Application filed October 28, 1911. Serial No. 657,283.

To all whom it may concern:

Be it known that I, GEORGE MILNE, a citizen of the United States, and a resident of the city of Chicago, county of Cook, and State of Illinois, have invented certain new and useful Improvements in Explosive-Engines, of which the following is a specification.

My invention relates to improvements in explosive engines and more specifically to means for cooling the cylinder of an explosive engine or for reducing the temperature therein when in operation.

The object of my invention is the production of means adapted to effect the cooling of the cylinder walls by the reduction of the temperature of the gases therein, and for maintaining the pressure lost by this method of cooling by the introduction of superheated steam into the cylinder.

A further object is the production of mechanism of the character mentioned which will be of economical construction, and positive and of high efficiency in operation.

Other objects will appear hereinafter.

With these objects in view my invention consists in the combinations and arrangements of parts hereinafter described and claimed.

My invention will be best understood by reference to the accompanying drawing forming a part of this specification, and in which,

Figure 1 is the side elevation of a conventional form of explosive engine to which is applied mechanism embodying my invention, the latter together with the upper end portion of the engine cylinder being shown in section, and Fig. 2 is a section taken on substantially line $x-x$ of Fig. 1.

The preferred form of construction as illustrated in the drawing comprises a substantially cylindrical chamber 1 which is formed integral with one head 2 of the cylinder 3 of the engine 4, the latter being of the conventional explosive type. The upper and lower ends of the chamber 1 are closed by screw plugs 5 and 6 respectively, the upper end of said chamber communicating with the upper end of the explosion chamber of the cylinder by means of a passage or port 7, the latter terminating within the chamber 1 in an internal circumferential groove 8 for a purpose which will become apparent as the description proceeds.

Communicating with the lower end por-

tion of the chamber 1 is a pipe 9 through the medium of which water under pressure is supplied to said chamber, said pipe communicating with any suitable source of water under pressure. The pipe 9 before reaching the chamber 1 communicates with an annular chamber 10 surrounding the exhaust pipe 11 of the engine. With this arrangement it will be observed, that when the engine is in operation, the water passing through the pipe 9 will be heated in the chamber 10 by the exhaust pipe before the same passes into the chamber 1. Provided in the pipe 9 adjacent the chamber 1 is an adjustable check valve 12 adapted to regulate the supply of water to said chamber and also to permit of the flow of water in the pipe only in a direction toward said chamber.

The passage 7 leading from the chamber 1 to the engine cylinder is governed by a sliding valve of peculiar construction which is mounted in the chamber 1. This valve is of two-part construction comprising an upper tubular or sleeve portion 13 and a lower substantially cylindrical or plug portion 14. The upper end portion of the part 14 which is reduced telescopes within the lower end of the part 13 as shown, it being freely slidable therein, the opposite sides of said end being cut away or flattened, as clearly shown in Fig. 2 to afford passages between the same and the adjacent internal surface portions of the valve part 13. The parts 13 and 14 are operatively connected by a transversely extending pin 15 which is carried in the upper end portion of the part 14, the respective extremities of said pin slidably engaging elongated slots 16 provided in the opposite sides of the part 13, the length of said slots evidently determining the amplitude of relative movement afforded the valve parts. The upper end portion of the chamber 1 is tapered downwardly as shown and the adjacent portion of the valve part 13 is correspondingly formed so that when said valve part is at its lower terminal of movement the same will be adapted to snugly seat in said portion of said chamber to effectually close communication between the chamber 1 and the passage 7 or with the annular groove 8 thereof.

Communication between the chamber 1 and the passage 7 is established when the valve part 13 is at its upper terminal of movement, radial openings 17 provided in said valve part 13 being adapted, 100

when said part is thus positioned, to register with the adjacent end of the passage 7 and the groove 8.

Elevation or upward movement of the 5 valve part 13 is effected through the medium of valve part 14, an inclined annular shoulder 18 of the part 14 being adapted to engage the correspondingly formed lower end of the part 13 so that, when the part 14 is elevated in the manner hereinafter set forth, the same after moving a short distance, will engage the lower end of the part 13 to move the same upwardly in the desired manner. The inclined shoulder 18, however, 10 constitutes a valve and the correspondingly formed end 19 of the part 13 its seat so that when said shoulder or valve 18 engages the end or seat 19 a tight connection will be effected which shuts off communication between the upper and lower ends of the chamber 1. A packing 20 is preferably arranged 15 in the exterior surface of the valve part 13 for engagement with the adjacent surface of the chamber 1 to insure a positive closing of communication between the 20 opposite ends of said chamber when the valve 18 and seat 19 are in closed position as set forth. With this arrangement it will be observed that upon upward movement of the valve parts 13 and 14, communication between the chamber 1 and the engine cylinder will be established and a 25 partial vacuum will be created in the lower end portion of the chamber 1. By reason of the partial vacuum thus created water will 30 be drawn into the lower end of the chamber 1 into the annular space surrounding the valve part 14 when the latter is moved into the larger upper end portion of said chamber 1; the check valve 12 being adapted to 35 be automatically opened by the suction created to permit of this passage of water from the pipe 9 into the chamber 1. A packing 21 preferably surrounds the lower 40 end portion of the valve part 14 to prevent any leakage in this direction. Upon the downward movement of the valve parts 13 and 14, the valve 18 will leave its seat 19 to 45 open communication between the respective ends of the chamber 1 and so as to admit of water drawn into the lower end of said chamber in the upward movement of said valve parts passing into the upper end of said chamber. This operation of valve parts 50 13 and 14 is effected by an arm 22 which is fulcrumed at 23 upon a lever 24 which is fulcrumed at 25 upon the supporting arm 26. The free end of the arm 22 is engaged and oscillated by a cam 27 which is carried 55 by the cam shaft 28, the latter being connected in the ordinary manner with the power shaft of the engine. It is clear that reciprocatory movement imparted to the arm 22 by the cam 27 during rotation of the latter will effect reciprocatory movement of

the valve part 14, the latter in turn contacting with and moving the valve part 13.

In operation the rotation of the cam shaft 28 will be so timed that upward movement of the valve parts to establish communication between the engine cylinder and the chamber 1 will take place just after the explosion in the cylinder or at the commencement of the power stroke. Some of the heated combustion generated in the engine 75 cylinder will pass through the passage 7 into the chamber 1 and there contact with the water contained in the upper end portion of said chamber. The heated gases thus contacting with the water will effect the 80 vaporization of the latter in the upper end portion of the chamber 1, the steam thus formed expanding into the cylinder and mixing with the gas thereby reducing the temperature thereof. The expansion of the 85 steam first mentioned will counter-balance the reduction in pressure of the cylinder gases caused by the reduction in temperature thereof so as to maintain the pressure in the cylinder. The reduction of pressure in an 90 engine cylinder caused by the cooling of the walls thereof through the medium of water jackets or other similar means which are generally in use at the present time is not compensated for in engines at the present 95 time and is lost. With my invention this will not be the case since the reduction of the temperature in the cylinder will be accompanied by a corresponding increase in the pressure so that no power will be lost 100 as in the case above set forth where cooling devices of ordinary construction are used. When the piston is near the end of its power stroke the valve parts 13 and 14 will be permitted to drop by gravity to close communication between the engine cylinder and the chamber 1, said valve parts remaining in this position during the exhaust, intake and pressure strokes, thereby preventing steam from mixing with the charge until after the 105 explosion takes place.

In starting the engine it is not desirous of introducing steam to the explosion chamber thereof as will be understood by those skilled in the art so that in starting the engine the lever 24 will be moved outwardly to withdraw the valve operating arm 22. When said arm 22 is in withdrawn position the cam 27 will have no effect upon the valve so that the latter will remain inert and hence communication between the chamber 1 and engine cylinder cut off. After starting of the engine the lever 24 will be moved to operative position the arm 22.

The preliminary heating of the water of 125 the pipe 9 in the chamber 10 is evidently of advantage since by so doing vaporization in the chamber 1 will more readily take place. The introduction of steam as above set forth into the cylinder of the engine is 130

also of advantage in that the steam thus introduced will serve to keep the spark plug clean, preventing the deposit of carbon thereon.

5 While I have illustrated and described the preferred form of construction for carrying my invention into effect, this is capable of variation and modification without departing from the spirit of the invention. I, 10 therefore, do not wish to be limited to the precise details of construction set forth, but desire to avail myself of such variations and modifications as come within the scope of the appended claims.

15 Having described my invention what I claim as new and desire to secure by Letters Patent is:

1. The combination with an explosive engine, of a chamber arranged adjacent to and 20 communicating with the cylinder of said engine, of a valve mounted in said chamber for controlling the communication between the cylinder and chamber; a water supply pipe communicating with the lower end of 25 said chamber; means for drawing water into the upper end; and means for simultaneously admitting hot gases from said cylinder to mix with the water in the upper part 30 of said chamber, upon the operative stroke of the engine piston, substantially as described.

2. The combination with an explosive engine, of a chamber arranged adjacent the cylinder of said engine; a passage connecting 35 the upper end of said chamber with said cylinder; a valve mounted in said chamber for governing said passage; a water supply pipe communicating with the lower end of

said chamber; and means whereby upon movement of said valve to open communication between said chamber and cylinder, water will be drawn into the lower end of said chamber, and whereby upon movement of said valve to closing position water will be forced into the upper end of said chamber; 45 and means for periodically operating said valve, substantially as described.

3. The combination with an explosive engine, of a chamber adjacent the cylinder of said engine; a passage connecting the upper 50 end of said chamber and said cylinder; a two-part valve mounted in said chamber for governing said passage; a water supply pipe communicating with the lower end of said chamber; a check valve in said pipe whereby when said valve is moved upwardly to open position water will be drawn into the lower end of said chamber, and whereby when said valve is moved downwardly to closing position, water will be forced into the upper end of said chamber, the parts of 55 said valve forming a second valve adapted when the said parts are moved upwardly to close communication between the upper and lower ends of said chamber and when said 60 parts are moved downwardly to open communication between said ends of said chamber; and means for periodically operating said valve, substantially as described.

. In testimony whereof I have signed my 70 name to this specification in the presence of two subscribing witnesses.

GEORGE MILNE.
